(57) **CLAIM**

The ornamental design for a loudspeaker, as shown and described.

DESCRIPTION

The file of this patent contains at least one photograph executed in color. Copies of this patent with color photographs will be provided by the Office upon request and payment of the necessary fees.

FIG. 1 is a front, top perspective view of a loudspeaker showing our new design.

FIG. 2 is a front elevational view thereof.

FIG. 3 is a side elevational view thereof; the other side being a mirror image.

FIG. 4 is a rear elevational view thereof.

FIG. 5 is a top elevational view thereof; and,

FIG. 6 is a bottom perspective view thereof.

The broken line showing of a logo in FIGS. 1 and 2 is for environmental purposes only and forms no part of the claimed design.
